CLAIM

The ornamental design for a serpentine panel, as shown and described.

DESCRIPTION

FIG. 1 is front elevational view of a serpentine panel, showing our new design;

FIG. 2 is a bottom plan view;

FIG. 3 is a top plan view;

FIG. 4 is an enlarged end elevational view;

FIG. 5 is an enlarged fragmentary front elevational view of an upper left-hand portion of the serpentine panel;

FIG. 6 is an enlarged fragmentary front elevational view of an upper center portion of the serpentine panel;

FIG. 7 is an enlarged fragmentary front elevational view of a lower center portion of the serpentine panel;

FIG. 8 is an enlarged fragmentary front elevational view of a lower left-hand portion of the serpentine panel;

FIG. 9 is an enlarged fragmentary front elevational view of an upper right-hand portion of the serpentine panel; and,

FIG. 10 is an enlarged fragmentary front elevational view of a lower right-hand portion of the serpentine panel.
